UNITED STATES PATENT OFFICE.

ENOCH C. RICHARDS, OF PORTLAND, MAINE.

CONCRETE-MOLD HOLDER.

Application filed September 25, 1926. Serial No. 137,712.

This invention relates to a mold for forming concrete walls, and including opposed mold members constituting the opposite sides of a mold cavity into which concrete 5 may be poured to form a wall, the mold members being capable of adjustment so that they may be located first in position to form the base portion of the wall, and then raised from time to time to form additions to the 10 base portion until a wall of the desired height is formed.

The object of the invention is to provide improved means for confining the mold members in each of the successive positions 15 required.

Of the accompanying drawings forming a part of this specification,—

Figure 1 is a perspective view of the frame and its adjuncts constituting one of 20 the units of a concrete mold-holder.

Figure 2 is a side view, showing two of the frames assembled with mold members.

Figure 3 is a section on line 3—3 of Figure 2.

Figure 4 is a view similar to Figure 3, showing a different adjustment.

Figure 5 is a fragmentary view, showing one of the frame members and one of the mold members inclined, to form a wall decreasing in thickness from its base upward.

Figure 6 is a fragmentary sectional view, showing the base and one of the uprights, adjusted for storage and shipment.

The same reference characters indicate the 35 same parts in all of the figures.

My improved holder is embodied in a frame and adjuncts thereof, constituting a unit of holding means, adapted to hold mold members of indeterminate length.

The frame comprises a base which, in this instance, includes a thin body portion 12, preferably a metal plate, and a thicker end portion 13, which may be a block of wood, or other material, secured, as by a bolt or 40 bolts 14 (Figure 6), to the body portion.

The frame comprises also two spaced apart uprights 15 and 16, engaged with the base, a tie member 17, connecting the upper ends of the uprights, a pair of mold confiners, 50 and a pair of mold supports. The confiners are preferably composed of substantially U-shaped slides 18, movable on the uprights, and hooks 19, pivoted to the slides. The mold supports are preferably composed of

55 substantially U-shaped slides 20, bolts 20^a inserted in the end portions of the slides,

and wedge-shaped chocks 21, interposed between the uprights and the bolts.

The hooks 19 are adapted to engage the upper edges of two opposed mold members 22, and confine said members against the uprights at various heights. The chocks 21 are adapted to bear on the lower edges of the mold members 22, and support the same at various heights. The upright 15 is fixedly secured to the base, preferably by means permitting the relative arrangement of said parts shown by Figure 6, to enable said upright and the base to be stored and transported in compact form, the securing means 70 preferably including a hinge 23, connecting the upright with the base portion 13, and a brace 24 attached at one end to the portion 13, and at its opposite end to the upright by a removable bolt or screw 25, so that the brace may be detached from the upright. The upright 16 is detachably secured to the base portion 12, preferably by a headed stud 26 and a keyhole slot 27 which 75 may be one of a plurality of alined slots, as shown by Figures 1 and 6. The head of the stud 26 is passed through the larger end of the slot, and the stud is then moved into the smaller end, so that the stud head is prevented from vertical withdrawal from the 80 slot. The upright 16, therefore, may be detached and stored compactly beside the upright 15 and the base.

The connection provided by the stud 26 and slot 27 is loose and permits the inclination of the upright 16 and the mold member 22 engaged therewith, as shown by Figure 5, so that the wall formed by the mold members may be tapered from its base upwardly. The tie member 17 is adapted to 90 engage the upper end of the upright 16, when the latter is inclined, as well as when it is vertical, the tie member being preferably pivoted at 28 to the upright 15, and provided with a plurality of notches 29, either of which is engageable with a detent 30 on the upper end of the member 16. Said notches and detent, the plurality of slots 27 in the base, and the stud 26 adapted to engage either of said slots, enable the uprights to be variably spaced apart, when the upright 16 is vertical and when it is inclined.

The hooks 19 and chocks 21 may be stored at random on the uprights, as indicated by Figure 1, when the frame is not in use. In preparing the frame for use, the slides 20

and chocks 21 are removed from the uprights, and two or more of the frames are deposited on a foundation, suitably spaced apart, as indicated by Figure 2. The mold members 22, which are preferably provided with spacing strips 22^a are then placed on the base portions 12, and the slides 18 are moved downward, to engage the hooks with the upper edges of the mold members, as shown by Figure 3. A wall portion W is then formed, by pouring concrete into the mold provided by the foundation and the mold members. When the concrete is sufficiently solidified, the mold members are raised and the slide 20 and chocks 21 are applied to the uprights, in position to support the raised mold members, as shown by Figure 4, the wedge-shaped chocks being forced tightly between the bolts 20^a and the uprights, so that the chocks and the slides 20 are firmly clamped on the uprights. A wall portion W' is then formed, by pouring concrete into the mold provided by the portion W and the mold members.

25 The last described operation may be repeated until a wall of the desired height is formed, the length of the uprights being sufficient to permit a suitable number of said operations. After the wall is completed, the upright 16 is detached from the base and the tie member, and the upright 15 and the base are then removed, the thin portion 12 of the base being readily withdrawable from the shallow recess formed thereby in the base 35 of the wall.

I claim:

1. A concrete mold-holder unit comprising a frame composed of a base, spaced apart uprights engaged with the base, and a tie member connecting the upper ends of the uprights; a pair of mold confiners movable on the uprights, a pair of mold supports movable on the uprights, the confiners being adapted to engage the upper edges of a pair of mold members and confine said members against the uprights at various heights, and the supports being adapted to bear on the lower edges of the mold members and support the same at various heights on the uprights, each support being composed of a U-shaped slide, a bolt engaged with the end portions of the slide and a wedge-shaped chock adapted to be interposed between the bolt and one of the uprights.
- 55 2. A concrete mold-holder unit comprising a frame composed of a base, spaced apart uprights engaged with the base, and a tie member connecting the upper ends of the uprights; a pair of mold confiners movable

on the uprights, a pair of mold supports movable on the uprights, the confiners being adapted to engage the upper edges of a pair of mold members and confine said members against the uprights at various heights, and the supports being adapted to bear on the lower edges of the mold members and support the same at various heights on the uprights, one of the uprights being fixedly secured to the base, and the other upright detachably secured thereto.

3. A concrete mold-holder unit comprising a frame composed of a base, spaced apart uprights engaged with the base, and a tie member connecting the upper ends of the uprights; a pair of mold confiners movable on the uprights, a pair of mold supports movable on the uprights, the confiners being adapted to engage the upper edges of a pair of mold members and confine said members against the uprights at various heights, and the supports being adapted to bear on the lower edges of the mold members and support the same at various heights on the uprights, the frame including a hinge connecting one of the uprights with the base, and a detachable brace connecting said upright with the base, so that the upright and base may be compactly stored when the brace is detached, the other upright being detachably connected with the base.

4. A concrete mold-holder unit comprising a frame composed of a base, spaced apart uprights engaged with the base, and a tie member connecting the upper ends of the uprights; a pair of mold confiners movable on the uprights, a pair of mold supports movable on the uprights, the confiners being adapted to engage the upper edges of a pair of mold members and confine said members against the uprights at various heights, and the supports being adapted to bear on the lower edges of the mold members and support the same at various heights on the uprights, one of the uprights being fixedly secured to the base, the base being provided with a plurality of key-hole slots, the other upright being provided at its lower end with a headed stud, adapted to separably engage either of said slots, so that the last-mentioned upright is adjustable, and the tie member being pivoted to the fixedly secured upright, and provided with a plurality of notches, either of which is engageable with a detent on the upper end of the adjustable upright.

In testimony whereof I have affixed my signature.

ENOCH C. RICHARDS.
